UNITED STATES PATENT OFFICE

106,187

DESIGN FOR A CLOSURE OR SIMILAR ARTICLE

Joseph R. Fleisch, Clifton, N. J., assignor to
Anchor Cap & Closure Corporation, Long
Island City, N. Y., a corporation of New York

Application January 15, 1937, Serial No. 67,072

Term of patent 14 years

To all whom it may concern:

Be it known that I, Joseph R. Fleisch, a citizen of the United States, residing in Clifton, county of Passaic, State of New Jersey, have invented a new, original, and ornamental Design for a Closure or Similar Article, of which the following is a specification, reference being had to the accompanying drawing, forming a part thereof.

Fig. 1 is a top plan view of a closure illustrating my new design; and

Fig. 2 is a front elevational view of the closure.

The dominant features of my design are cir-

cumferentially spaced, alternating wide and narrow grooves extending from the top of the skirt of the closure and terminating short of the bottom of the skirt. The wide grooves, when viewed from the top of the closure, are in the shape of an arc or segment of a relatively large circle, while the narrow grooves are an arc or segment of a substantially smaller circle.

I claim:

The ornamental design for a closure or similar article, substantially as shown and described.

JOSEPH R. FLEISCH.
